UNITED STATES PATENT OFFICE.

WILLIAM W. WERT, OF DAYTON, OHIO.

AEROPLANE.

1,418,502.

Specification of Letters Patent. Patented June 6, 1922.

Application filed June 4, 1917. Serial No. 172,723.

To all whom it may concern:

Be it known that I, WILLIAM W. WERT, citizen of the United States, residing at Dayton, in the county of Montgomery and State of Ohio, have invented certain new and useful Improvements in Aeroplanes, of which the following is a specification.

My invention relates to flying machines of the heavier than air type and more particularly to an aeroplane of double plane twin construction and control.

The object of the invention is to improve the construction as well as the means and mode of operation of such flying machines whereby they will not only be cheapened in construction but will be more efficient in use, positive in operation, uniform in action, and unlikely to get out of repair.

A further object of the invention is to provide improved stabilizing means which will not only afford a supplemental lifting effort but which will materially assist in banking or tilting the machine to the required angle when flying in arcuate or curved paths of travel.

A further object of the invention is to provide improved control means which will be continuously and equally under the control of either one of two operators independent of the other.

A further object of the invention is to provide an improved form of chassis which will enable the machine to be guided while running upon the ground either during its initial starting operation or during the landing operation.

A further object of the invention is to provide an improved construction for utilizing the air currents produced by the movement of the machine and for deflecting objectionable currents in order that they may not disturb the equilibrium of the apparatus.

A further object of the invention is to provide improved steering and controlling means and an improved operative connection therefor whereby said means may be independently controlled from different stations or by different operators.

With the above primary and other incidental objects in view as will more fully appear in the specification, the invention consists of the features of construction, the parts and combinations thereof and the mode of operation or their equivalents as

hereinafter described and set forth in the claims.

Referring to the drawings, Fig. 1 is a top plan view of the assembled machine one half of which is shown in skeleton form. Fig. 1^a is a continuation of Fig. 1 illustrating the rear of the machine broken away at the left in Fig. 1. Fig. 2 is a side elevation of the assembled machine. Fig. 2^a is a continuation of Fig. 2 from the point where broken away at the left in Fig. 2. Fig. 3 is a front elevation of the machine as viewed from the right in Fig. 1 and Fig. 2. Fig. 4 is a longitudinal sectional view of the interconnecting portion of the main frame at the operating position illustrating the operator's seat and control devices. Fig. 5 is a top plan view of a locking detent for the control apparatus. Fig. 6 is a detail perspective view of a foot operated detent for a portion of the control mechanism. Fig. 7 is a top plan view somewhat diagrammatic, illustrating the control system of levers, links and cables and parts operated thereby together with the driving connections independent of the frame or structure of the apparatus itself. Fig. 7^a is a detail view. Fig. 8 is a detail perspective view illustrating the construction and bracing or reinforcement of the supporting planes. Fig. 9 is a detail perspective view of the strut and guy or brace connection. Figs. 10 and 11 are details of the frictional clutch driving connection.

Like parts are indicated by similar characters of reference throughout the several views.

Briefly stated, the aeroplane forming the subject matter hereof is of twin double plane construction and embodies twin control and driving mechanism under the constant control of either one of two operators whereby if any accident shall befall one of the operators, the other may exercise absolute control over the machine without changing his position. The construction also embodies twin stabilizing means. The structure comprises two pairs of transversely arranged superposed supporting planes hereafter referred to as the "fore planes" and the "aft planes" which are connected by a longitudinally disposed backbone or body structure within which the operators' stations are located. This backbone or body structure extends rearward beyond the aft planes and

terminates in both elevating and lateral guiding rudders. Stabilizing helicopters are arranged in fore and aft pairs immediately abaft the supporting planes and to the 5 rearward of the equalizing or stabilizing helicopters are located ailerons which assist in the guiding and controlling operation. The lateral guiding rudders at the rear of the structure are interconnected with the 10 carrying wheels at the front of the chassis whereby said guiding rudders and carrying wheels are operated in unison under influence of the steering devices from the operators' stations. The motive power is supplied by fore and aft pairs of rotary propellers located immediately forward of the respective supporting planes and driven by separate motors which motors also actuate the respective fore and aft pairs of 15 helicopters. Inasmuch as the fore and aft sets of supporting planes, stabilizing helicopters and ailerons together with their driving connections are substantially the same, a detailed description of one set will suffice for 20 both. The several parts and elements of the respective sets of supporting, stabilizing and control devices before mentioned are indicated by the same reference characters upon the drawings, those parts of the aft sets, 25 however, being distinguished from those of the fore sets by the addition of prime marks.

Referring to the drawings, 1 is the upper supporting plane and 2 the lower plane connected one to the other by vertically disposed struts 3. These planes are arcuate in a fore and aft direction and are inclined slightly upwardly and forwardly as indicated more particularly in Fig. 2. The frame of each plane comprises transversely 35 disposed marginal bars or slats 4—4 connected one to the other by ribs 5 longitudinally disposed in relation with the general design of the machine. The ribs 5 are curved to agree with the arcuate contour of the 40 planes. The ribs 5 are provided with a series of holes 6 through which are laced a series of wires 7 to form a woven open mesh screen or network for the support of the fabric coverings. This network of wires 7 further 45 tends to strengthen the frame of the plane to prevent buckling or yielding while in use. The frame is further strengthened by arcuate terminal ribs 8 connecting the ends of the marginal bars or slats 4. These arcuate terminal ribs also form supports for the 50 interwoven or laced wires 7. In addition to the reinforcement afforded by the interwoven wire lacings 7 the frames are further braced by diagonally disposed brace wires 55 or guys 9. These brace wires are preferably locked or intertwined one upon the other at their points of intersection. The fabric coverings of the planes are preferably two-fold, one thickness or fold being disposed 60 beneath the ribs 5 and interlaced supporting 65

wires 7 and the other thickness or fold overlying such ribs and wires. However, either one of the thicknesses of material may be dispensed with and a single thickness employed which may extend either above or beneath the ribs and wires 7 as found most desirable. Mounted in suitable brackets or bearings 10 and extending parallel with the marginal slats or bars 4 of the plane frames are revoluble roller rods or shafts 11 to 70 which the marginal edges of the fabric plane covering are attached. By the rotation of these roller rods or shafts the covering fabric may be stretched to any desired degree of tension. When the desired tension has 75 been acquired the roller rods 11 may be locked in their bearings while supplemental slats or bars 12 complementary to the frame bars 4 are laid upon the stretched fabric and clamping bolts passed through said superposed bars 12 and 4 to clamp the margins of the fabric between said bars. It will be understood of course that said clamping bolts not only pass through the bars 12 and 4 but also through puncture holes in the interposed strata of fabric. 80

As before mentioned, the supporting planes 1 and 2 and 1' and 2' are connected one to the other by interposed struts or standards 3 and 3'. These struts are provided with terminal fittings 13 shown in detail in Fig. 9 in which the ends of the struts are seated. These fittings embody laterally disposed lugs 14 terminating in perforated heads with which are engaged eye bolts or 95 swivels 15 comprising the terminal ends of diagonally disposed guy wires or braces 16. These braces or guy wires 16 not only extend from the upper to the lower planes in longitudinal diagonal directions, but also 100 in transverse diagonal directions as shown in Figs. 2 and 3. These diagonal guys or braces together with the diagonal braces 9 serve to connect the planes into a staunch 105 stable structure. 110

The longitudinal frame or backbone of the machine comprises a longitudinally disposed tubular enclosed framework 17 which extends from a point in advance of the forward planes to a point abaft the rear planes. The longitudinal frame or backbone of the machine comprises a series of circular frame members or hoops 18 connected one with another by longitudinally disposed side bars 19. The structure thus formed is braced by 115 interwoven wire lacings 20 which serve to give a continuous contour or shape to this tubular body and serve to support the envelope or covering. Within the tubular housing thus formed are located various 120 portions of the control and actuating mechanism. Supported upon the tubular frame or backbone are a plurality of vertically disposed struts or standards 21 supporting a longitudinally disposed canopy 22. This 125 130

canopy 22 comprises substantially a longitudinally disposed supporting plane extending fore and aft approximately on level with the upper main supporting planes 1 and 1'. This fore and aft plane or canopy is formed arcuate with its concave side downward. There is thus provided a centrally disposed fore and aft alleyway or air passage extending substantially the entire length of the machine through which currents of air may pass while confined beneath the domed canopy or longitudinal plane. This plane is composed of a suitable framework embodying longitudinal bars or slots 24 connected by transverse ribs 25, the structure being strengthened and braced by interwoven wire lacings as before described. The supporting struts are further supported and braced by both longitudinally and transversely disposed diagonal guys or braces 26. At its rear end the longitudinal frame or backbone of the apparatus is provided with a terminal spatulation 27 to the rear edge of which is hinged an elevation rudder 28 oscillating about a horizontal axis. Co-incident with the spatulation 27 and oscillating about a vertical axis is a lateral guiding rudder divided into upper and lower sections 29 and 30 situated above and below the terminal spatulation 27 but connected to a common support and movable to and fro in unison.

Located immediately in the rear of each of the upper supporting planes and upon opposite sides of the longitudinal plane 22 are spherical domes 31 forming parts of the main framework of the machine and fixedly connected with the frame structure. These spherical domes each comprises a suitable frame including an annular or hoop-like marginal member 32 to which are connected arcuate radially disposed ribs 33 connected each to the other by circular wires or hoops 34 and over which is fitted a fabric covering 35. Within these domes are mounted helicopters 36 which afford a stabilizing effect upon the machine while in flight and assist in banking or tilting the machine when flying a curved course. Immediately to the rear of the helicopter domes just described are ailerons or drag wings 37 mounted for oscillatory movement about horizontal axes. These ailerons materially assist in stabilizing the apparatus and maintaining it upon even keel and further assist in varying the elevation or inclination of flight. The main structure thus far described is mounted upon a chassis comprising substantially arch-shaped transverse frame members 38 attached at the crown of the arch to the underside of the main structure and braced forwardly and rearwardly by suitable diagonal braces 39. Upon the lower ends of the arch-shaped members 38 are pivoted carrying wheels 40 which may be of any suitable type but are preferably wire spoked pneumatic tired wheels of the bicycle type. The forward wheels 40 are mounted upon swiveled or knuckle spindles as indicated at 41 similar to the mounting of automobile guide wheels. The actuating arms 42 of the knuckles 41 are connected to move in unison by a transverse connecting rod 43. In the drawing this connecting rod 43 has been shown provided with a centrally disposed stud 44 engaging in the slot 45 of a rock arm 46 carried upon the lower end of a steering post 47 vertically disposed in the frame. The steering post 47 carries at its upper end a cross arm 48. This cross arm 48 is interconnected through the steering and control mechanism with the rudder sections 29 and 30 at the rear of the machine whereby said rudder sections and the forward carrying wheels 40 will be oscillated in unison. Thus the machine may not only be controlled while in flight, but also while making a running start and while running upon the ground after landing. In both instances the controlling operation is effected by the same control or steering mechanism.

The apparatus is controlled by four revolving helicoidal propellers 50 and 50' rotating in vertical planes immediately in front of the respective pairs of supporting planes. These revoluble propellers are mounted on suitable supporting shafts 51 mounted in the main structure. The forward and rearward propellers are independently actuated by separate driving motors 52 and 52' mounted in central positions aligned with the backbone or longitudinal portion of the machine. The crank shaft 53 of the motor extends forwardly and is supported in suitable bearings 55. The shaft 53 carries a gear pinion 56 at one side of the bearing 55 and a sprocket wheel 57 at the fore side. The gear 56 meshes with a similar gear 58 upon a counter shaft mounted in a bearing 59 similar to the bearing 55. This counter shaft carries at its forward end a sprocket 60 similar to the sprocket 57. The sprockets 57 and 60 are connected by sprocket chains or driving belts 61 with sprockets or drive pulleys 62 carried upon the shafts 51 adjacent to the propellers 50 whereby said propellers are simultaneously rotated in opposite directions. The crank shaft 53 of the motor 52 is also extended rearwardly through a bearing 63 and carries at its extremity a gear 64. The gear 64 meshes with a similar gear 65 upon a counter shaft mounted in a bearing 66. Loosely journaled upon both the crank shaft 53 and the counter shafts before mentioned, adjacent to the bearings 63 and 66, are loose sprockets or pulleys 67 and 68 adapted to be intermittently connected with the respective drive shafts by friction clutches. This clutch is illustrated in detail in Fig. 11.

The sprockets or pulleys 67 and 68 are connected by sprocket chains or belts 69 with corresponding sprockets or pulleys 70 on counter shafts mounted in bearings 71 which 5 shafts carry bevel gears 72 meshing with corresponding gear pinions upon the vertical shafts 73 of the helicopters 36. By this driving train, the helicopters 35 and the propellers 50 may be simultaneously driven 10 from the same motor 52. However, by releasing the drive pulleys or sprockets 67 and 68 by the disengagement of the friction clutches pertaining thereto, either the right or the left helicopter may be operated independent 15 of the other or both helicopters may be disconnected from the driving motor and permitted to operate idly. While any form of friction clutch may be employed, in Fig. 11 there has been illustrated a simple yet efficient 20 construction. To this end the driving sprocket or pulley 67 is provided with an integral annular flange or rim 74. Upon the driving shaft within the rim 74 is mounted a disk 75 which supports a split 25 ring 76. This split ring 76 is adapted to be expanded into peripheral contact with the interior of the rim or flange 74 by the oscillation of an operating lever 77 pivoted to the disk 75 intermediate the ends of the split 30 ring 76. This operating lever is actuated by a reciprocating cone 78 slidably mounted upon the drive shaft and actuated from the operators' or drivers' stations as hereinafter described.

35 The drivers or operators, of which there may be two, are stationed in cock pits formed in the tubular backbone or longitudinal body of the structure and surrounded by coamings 80 within which are located seats 81" for the drivers. Located adjacent to each driver's 40 position, are two helicopter control levers, one on each side of the station, and controlling the two right and the two left helicopters respectively. The corresponding levers are connected one to the other to operate in unison. Referring particularly to Figs. 2 and 7, these levers 81 and 81' are pivoted concentric with notched locking segments 82 and are each provided with a pinch lever 83 controlling the locking bolt 84 which engages in the 45 notched segments 82 to retain the lever in its adjusted position. The levers 81 and 81' are connected one to the other by an intervening reciprocating link 85 whereby the oscillation of one lever will be transmitted to the other lever, causing said levers to move in unison. The pinch levers 83 of the respective levers are also connected one to the other by intermediate cables or wires 86 whereby the releasing and locking movements of one pinch lever are transmitted to the pinch lever of the other control lever. Connected to each of the control levers 81 and 81' to move in unison therewith, are rock arms 87 and 87' connected respectively by links or rods 88 and

88' with shift rods 89 adapted by their reciprocation to cause the engagement and disengagement of the helicopter control clutches. The construction is such that either driver by compressing the pinch lever 83 of his particular control lever 81 may unlock both the levers 81 and 81' and by the oscillation of his particular lever, both levers are simultaneously oscillated thereby engaging or disengaging both the forward and rear helicopters upon the corresponding side of the apparatus. As before mentioned, the helicopters fore and aft upon one side of the apparatus may be operated independent of those upon the other side. When disconnected the helicopters may operate idly under the influence of the air currents as the machine advances. In order to avoid resistance to the advance of the apparatus by the rotation of the helicopters, that is to say, in order that the helicopters may not oppose the movement of air currents, the helicopter domes 35 are provided with pendent coamings or baffles 89 extending about their inner forward quadrants connecting with the outer forward ends of 90 which are divergent pendent deflectors or baffles 90 supported beneath the upper supporting planes and extending rearwardly and outwardly. The helicopters 36 rotating in the direction indicated by the arrows in Fig. 95 1 will traverse their forward movement within the protection of the baffles 89 and 90 and will receive the rear rushing air currents during the rearward half of their rotation, whereby the currents will tend to accelerate 100 the rotation of the helicopters and the latter will not retard the advance of the apparatus. When the helicopters have been released from the driving motor they will continue to rotate while the machine is in action under 105 the influence of the air currents thus automatically yielding to air pressure and obviating any retarding effect. It will be understood that the operation of the helicopters upon one side of the apparatus independent 110 of those upon the other side will tend to tip or tilt the machine laterally assisting in the banking upon a curved course. The operation of both helicopters simultaneously tends to elevate the apparatus upon even beam. 115 The helicopters may be normally operated in unison and continuously while in straight flight and one lateral pair of helicopters disconnected when turning, or said helicopters may all be normally disconnected and one 120 lateral pair or the other pair brought into operation only upon occasion of curved flight. In order to provide for the control of the apparatus, whether running upon the carrying wheels 40, or while in flight, means is 125 provided whereby either driver independent of the other, may vary in unison the lateral inclination of the rudder sections 29 and 30 and the forward carrying wheels 40. To this end the common vertical supporting shaft of 130

the rudder sections 29 and 30 is provided with a cross arm 91 secured thereto, similar to the cross arm 48 of the steering post 47. Located adjacent to each driver's station 5 and within reach of his seat while seated in the operating position are pivoted cross arms 92 and 92' adapted to be oscillated by the foot action of the driver. Each of the cross arms 48, 91 and 92 carry at their opposite extremes 10 pivoted rockers 93. The cross arm 92' is also provided with rockers 93' which, however, instead of being loosely mounted are secured to the cross arm 92' which in turn is rotatably mounted in an oscillatory supporting head 94. The cross arm 92' carries a pendent arm 95 connected by a cable or wire 96 with a reciprocating bolt 97 adapted to engage any one of a series of notches in a segment 98 positioned intermediate the driver's station. The segment 98 carries with it a cross arm 99 which is also provided with loosely pivoted rockers 93. Both the upper and lower arms of the rockers 93 of the cross arms 48, 91, 92, 92' and 25 99 are connected one with another by longitudinally disposed wires or cables 100 whereby a rocking movement of any one of the rockers 93 will be transmitted to the other rockers of the series. The rockers 93 carried by the cross arm 92 and 92' form foot rests or pedals for the driver. The particular object of the oscillatory movement of the rockers is to enable either driver by the oscillation of said rockers to rock the cross arm 30 92' and with it the pendent rock arm 95, thereby withdrawing the bolt 97 from locking engagement with the segment 98 which releases the cross arm 99 to which the cables 100 are also connected. The locking bolt 97 having been disengaged by the oscillation of the rockers or pedals which movement is transmitted idly to the rockers of the arms 48, 91 and 99, the cross arms may then be oscillated laterally by the foot action of 45 the driver to reciprocate the wires or cables 100 at the opposite sides of the apparatus in opposite directions, that is—forwardly and rearwardly respectively. It is to be noted particularly by reference to Fig. 7 that the wires or cables 100 are reversed or crossed intermediate the cross arm 91 of the rudder sections 29 and 30 and the cross arm 92' at the rear driver's station. This enables the rudder sections 29 and 30 to be 50 turned to guide the apparatus in a direction agreeing with that of the inclination of the forward carrying wheels 40 effected by the oscillation of the cross arm 48 carried by the steering post 47. Thus either driver may 55 by the oscillation of the pedals or rocker members 93 unlock the steering apparatus and thereafter by the turning or oscillation of the cross arm by which the pedals or rockers are carried, he may simultaneously 60 oscillate the forward carrying wheels 40 and the rear guiding rudder sections 29 and 30 in opposite directions whereby the rudders and the wheels will coact and assist each other in the turning of the apparatus when running upon the ground, the said carrying 65 wheels being moved idly while in flight.

In order to guide the apparatus vertically, there is provided at each driver's station, a steering wheel 101 upon the post 102 of which is carried a notched locking 70 segment 103. Supported upon a suitable bracket 104 adjacent thereto is an oscillatory pedal member 105 having a detent or locking finger 106 adapted to engage any one of a series of notches of the locking segment 75 103. These oscillatory pedal members 105 are connected one to the other to rock in unison by means of cables or wires 107. The structure is such that either driver by rocking the pedal member pertaining to his station may unlock both steering wheels 101. Carried upon the steering post 102 is a sprocket wheel or pulley 108 around which passes a cable or belt 109 extending through 80 guide pulleys 110 in the frame of the structure and connected to the ailerons or drag wings 37. In practice, a sprocket wheel 108 is preferably used about which extends a short length of sprocket chain to the ends of which the cable 109 is attached. The 85 guide pulleys 110 are so located in the frame or structure in relation with the pivotal points of the ailerons 37 that when the steering wheel is oscillated to reciprocate the cable in one direction the ailerons will be 90 depressed and when oscillated in the opposite direction they will be elevated. It will be understood that the construction is such that the rotation of the sprocket wheel 108 will exert a pulling effect upon one side of the cable 109 and will pay out or slacken the opposite side of said cable. Located upon the rear steering post 102' is a similar sprocket wheel or pulley 111 controlling a cable 112 passing through suitable guide 95 pulleys 113 and having its opposite end connected to the rearmost ailerons or drag wings 37'. The construction and operation of this cable connection is the same as that before described. At the lower ends of the 100 steering posts 102 and 102' are bevel gear pinions 114 meshing with similar gear pinions 115 to which are attached sprocket wheels carrying a sprocket chain or belt 116. The arrangement is such that upon the release of the steering post 102 by the oscillation of the pedal detent 106 out of engagement with the locking segment 103 the controlling movement of either of the steering wheels 101 will be transmitted through 105 the gears 114 and 115 and the connecting sprocket chain or belt 116 to the other steering post. The respective steering posts and the cables 108 and 112 controlling the fore and aft ailerons 37 and 37' are thereby 110 120 125 130 135 140 145 150 155 160 165 170 175 180 185 190 195 200 205 210 erated in unison from either driving station. There is also mounted upon the rearmost steering post 102' a second sprocket wheel 117 controlling a belt or cable 118 which 5 passes through suitable guide pulleys 119 in the frame of the machine and thence to the elevating rudder 28. This control cable like the cables 108 and 112 is so arranged that the opposite sides of the cables are reciprocated 10 in opposition, that is, as one side is tightened to move the ailerons in one direction, the other side is slackened to compensate for such movement. It will be understood that the guide pulleys in each instance are so 15 arranged in relation with the pivotal connection of the ailerons as to transmit the pulling effort upon the cables in such direction as to cause a corresponding variation of the ailerons.

20 While independent control means has heretofore been described for the helicopters and the guiding wheels and rudder it will be obvious that the clutch shifter by which the helicopters are connected and disconnected 25 may be connected for operation directly with the wires or cables 100 in lieu of being connected to the levers 81 and 81'. By this arrangement the right or the left pair of helicopters would be automatically 30 connected in accordance with the corresponding deviation of the apparatus from a straight path of travel. The connection of this clutch shifting device with the control cable 100 is so simple as to be readily understood without the necessity of illustration.

Although the structure has been shown and described as an integral apparatus it will be obvious that it may be so constructed 40 that the forward portion, that is, the forward supporting planes, together with the portion of the backbone or main frame intermediate the fore and aft planes may be disconnected from the rear portion of the machine, leaving the rear supporting planes and helicopters, together with the steering rudders intact. Inasmuch as the rear propellers and helicopters are driven from a separate motor located at the rear of the machine, it will be obvious that such separated rear portion might be used as a single aeroplane of small capacity.

By the constructions hereinbefore set forth the operation of the apparatus is constantly under the control of either of two drivers or operators. There are two sets of control devices all adapted to be locked in their adjusted positions, the releasing of which may be effected from either driving 50 station.

From the above description it will be apparent that there is thus provided a device of the character described, possessing the particular features of advantage before 65 enumerated as desirable but which obvi-

ously is susceptible of modification in its form, proportion, detail construction or arrangement of parts, without departing from the principle involved or sacrificing any of its advantages.

70 While in order to comply with the statute, the invention has been described in language more or less specific as to certain structural features, it is to be understood that the invention is not limited to any specific details, but that the means and construction herein described comprise but one mode of putting the invention into effect, and the invention is therefore claimed broadly in any of its possible forms or modifications within the scope of the appended claims.

75 Having thus described my invention, I claim:—

80 1. In a flying machine of the character described, a longitudinally disposed back bone or main frame structure, two pairs of superposed supporting planes transversely arranged relative to the back bone or main frame, said pairs of planes being arranged 85 in tandem relation, a pair of helicopters arranged contiguous to the rear edges of each of the pairs of supporting planes and rotating substantially in common planes therewith, the individual helicopters of each 90 pair being positioned on opposite sides of the back bone or main frame, guiding rudders carried upon the main frame, actuating propellers, and means for independently actuating the individual helicopters of each 95 pair, substantially as specified.

2. In a flying machine, the combination 100 with a main frame, a lifting and supporting plane, propelling and guiding means, of a pair of helicopters the members of which 105 are located contiguous to the rear edge of the supporting plane at opposite sides of the medial line of the machine, dome-shaped rearward extensions from said plane overhanging said helicopters, and means for 110 actuating said helicopters each independent of the other.

3. In a flying machine, the combination 115 with a main frame, a supporting plane transversely arranged in relation to the main frame, propelling and guiding means of a pair of helicopters the members of which are located at opposite sides of the medial line of the machine, a dome or concave housing fixed upon the main frame in the 120 rear of said transversely arranged plane beneath which each helicopter rotates, and means for actuating the helicopters each independent of the other.

4. In a flying machine the combination 125 with a main frame, a transversely arranged lifting and supporting plane, propelling and guiding means, of rearward extensions from said supporting and lifting plane, a pair of helicopters the members of which 130

- are located beneath the rearward extensions of the plane at opposite sides of the medial line of the machine, means for actuating the helicopters in unison, and means for releasing one helicopter from the actuating means independent of the other helicopter. 5
5. In a flying machine, the combination with a main frame, a supporting plane, propelling and guiding means, of a pair of 10 helicopters the members of which are located at opposite sides of the medial line of the machine, a baffle positioned in advance of each helicopter beyond which only the receding or rearwardly rotating portion of 15 the helicopter is exposed to the air currents, and means for actuating the helicopters. 10
6. In a flying machine, the combination with a main frame of supporting planes one arranged in advance of the other, and a 20 propeller of a longitudinally disposed plane medially connecting the fore and aft planes, helicopters located on opposite sides of said medial longitudinally disposed plane, and means for actuating said propeller and heli- 25 copters.
7. In a flying machine, the combination with a main frame, a supporting plane, and a propeller, of two independently operable helicopters located on opposite sides of the 30 medial line of the machine, and at the rear of the supporting plane and ailerons located to the rear of said helicopters. 30
8. In a flying machine, the combination with a main frame, a transversely arranged
- supporting plane and propelling means of 35 two domed enclosures contiguous to the rear edge of the plane helicopters positioned beneath said domes, the structure being lifted and sustained in flight solely by said supporting plane, while the helicopters ex- 40 pert an equalizing and balancing action upon the structure while being sustained by said supporting plane, and means for actuating the helicopters in unison or one independent of the other, at the will of the operator. 45
9. In a flying machine, the combination with a main frame, a supporting plane and propelling means, of helicopters adjacent to said planes and air fenders about the periphery of the forwardly rotating halves 50 of the helicopters, the peripheries of the rearwardly rotating halves of the heli- copters being exposed in a forwardly direction.
10. In a flying machine, the combination with a main frame, a supporting plane and propelling means, of ailerons in the rear of the plane and helicopters intermediate the ailerons and supporting plane and contiguous to both, substantially as specified. 55
- In testimony whereof, I have hereunto set my hand this 23rd day of May A. D. 1917. 60

WILLIAM W. WERT.
